UNITED STATES PATENT OFFICE.

ALBERT T. LOFTSGAARDEN, OF POWELL, WYOMING.

HAYSTACKER.

1,425,399.

Specification of Letters Patent. Patented Aug. 8, 1922.

Application filed March 12, 1921. Serial No. 451,739.

To all whom it may concern:

Be it known that I, ALBERT T. LOFTSGAARDEN, of the city of Powell, in the county of Park and State of Wyoming, have invented certain new and useful Improvements in Haystackers, of which the following is a specification.

This invention relates to improvements in hay stackers and the primary object of 10 the invention is to furnish a hay stacker embodying a combined oscillating and slide- able elevator, designed to receive hay while in horizontal position and then to be swung about its fulcrum and extended to elevate 15 the load.

Another object of the invention is to furnish a device of this character with im- 20 proved means forming an extension for the base of the apparatus so that the device may be used on rough hard ground without driv- 25 ing stakes or the like to anchor the appa- ratus.

A further object of the invention is to furnish a device of the type indicated with 25 improved means for simultaneously swing- ing the elevating mechanism about a hori- zontal axis and extending the same longitudi- 30 nally. The apparatus includes means for swing- ing the elevator frame without extend- 35 ing the elevator, and it also includes means for simultaneously carrying out these opera- tions.

With the foregoing objects outlined, and 35 with other objects in view which will ap- 40 pear as the description proceeds the inven- tion consists in the novel features herein- after described in detail, illustrated in the accompanying drawings and more particu- 45 larly pointed out in the appended claims.

Referring to the drawings:

Figure 1 is a perspective view of my im- 45 proved apparatus showing the elevator frame raised and the elevator itself in low- ered position.

Fig. 2 is a top plan view of the apparatus shown in substantially collapsed position.

Fig. 3 is a side view of the apparatus showing the elevator frame and elevator in the horizontal position which they occupy 50 before receiving the load to be elevated.

Fig. 4 is a similar view showing the ele- 55 vator frame swung into substantially verti- cal position and the elevator raised.

Fig. 5 is a diagrammatic view of the va- 55 rious ropes and pulleys used for manipulat- ing the apparatus.

Fig. 6 is a detail perspective view of the upper end of the elevator frame and showing certain ropes connected to the same.

Fig. 7 is a perspective view of one of the 60 blocks forming the extension for the appa- ratus base.

In the drawings, 1 designates a base de- 65 signed to rest in horizontal position on the ground upon which the apparatus is erected and including side bars 1^a and 1^b having their ends connected together by bars 1^c, 1^d. The base is braced by means of a V-shaped bracket 1^e which has its central portion se- 70 cured to the bar 1^d and its ends extended through the side bars of the base as shown at 1^f to provide pivot pins for the elevator frame which will be hereinafter described.

In order to prevent the apparatus from 75 toppling over when the elevator frame is raised into substantially vertical position, I provide a base extension consisting of blocks 2 which extend beyond one end of the frame and are provided with latching 80 members 2^a and 2^b. The members 2^a engage the front ends of the bars 1^a and 1^b and the members 2^b rest on the upper surfaces 85 of the side bars of the base. With the use of this extension, the base of the apparatus will be prevented from toppling over and it will not be necessary to employ stakes or other anchoring means which must be driven into the soil.

3 designates the elevator frame which is 90 provided at its lower end with fulcrum blocks 3^a that are pivotally connected to the pins 1^f. This connection permits the frame 3 to be placed in a position parallel with the base 1 or to be moved into a position 95 substantially perpendicular to the base. The elevator frame includes pairs of side bars 3^b, 3^c and each pair of these bars have their lower ends secured to the fulcrum blocks 3^a, and are spaced apart throughout substan- 100 tially their entire length to provide elevator guides 3^d. The upper ends of the bars of each pair 3^b and 3^c are spaced apart and connected together by rectangular collars 3^e. The upper ends of the bars 3^b are secured 105 together by a cross bar 3^f and the upper ends of the bars 3^c are connected together by the cross bar 3^g. The lower ends of the side bars of the elevator frame are connected together and braced by means of a cross bar 3^h. The bars 3^b, 3^c, 3^f, 3^g and 3^h form 110 a substantially rectangular elevator frame and this frame is braced by means of a

V-shaped bracket 3^b which has its central portion secured to the bar 3^c and its ends connected to the bars 3^b.

The elevator frame supports an elevator 4 consisting of a head 4^a and side bars 4^b. The side bars are slidably mounted in the guides 3^a and they are provided at their lower ends with plates 4^c which are secured to the elevator side bars on opposite sides 5 of the bars 3^b and 3^c and slidably engage the last mentioned bars. It will thus be seen that the elevator may be extended relatively to the elevator frame 3 and the side bars 4^b slide through the collars 3^a at the upper 10 ends of the side bars of the elevator frame 3.

The mechanism for swinging the elevator and elevator frame from horizontal position to a substantially vertical position and for extending the elevator relatively to the 20 elevator frame, includes a derrick 5 which is of V shape and consists of side bars 5^a having their lower ends pivotally connected at 5^b to the side bars of the base 1. The upper or outer ends of the side bars 5^a are connected to a head 5^c and by viewing the 25 drawings it may be seen that the derrick 5 may be swung from the position shown in Fig. 3 to the positions shown in Figs. 1 and 4.

30 One of the means for swinging the derrick from one position to another consists of a rope or cable 6 having one of its ends secured to a pulley 6^a which is connected to the head 5^c. The rope 6 is extended from 35 the pulley 6^a through a pulley 6^c carried by the end bar 1^d of the base and from the pulley 6^c it is passed around the sheaf of the pulley 6^a and is then returned over the sheaf of the pulley 6^c and extended outwardly, and its end 6^b is designed to be secured to the single tree 11^a or other drawing mechanism for the purpose of tensioning the rope 6 and causing the bar 5^c of the derrick to be swung toward the bar 1^d. The 40 head of the derrick is connected by cables 7 to the upper or outer end of the elevator frame 3, and it will be seen that the ropes 7 are connected to the derrick at the point 7^a and to the elevator frame at the points 7^b.

50 A rope 8 is provided for steadyng the elevator frame while the same is being raised and this rope has branches 8^a which are secured to the upper end of the elevator frame as best shown in Fig. 4. The lower end of 55 the rope 8 is connected to one end of a coil spring 8^b, the other end of the spring being secured to the cross-bar 1^c, and the spring functioning to aid in returning the elevator frame to its horizontal position.

60 From the foregoing it will be understood that when the elevator is in horizontal position as shown in Fig. 3, hay or the like may be placed on the elevator head 4^a and then by drawing on the rope 6 the pulley 6^a will 65 be drawn towards the pulley 6^c and this

will cause the derrick to swing on its pivots 5^b, and the ropes 7 to swing the elevator frame on its pivots 1^c. This mechanism above described will swing the elevator frame and elevator without causing the 70 elevator 4 to be extended and this is desirable in cases where the load is to be raised only short distances.

In order, however, to cause the elevator to be extended simultaneously with the 75 swinging of the elevator frame 3 on its pivots 1^c I have provided the following mechanism. Ropes or cables 9 have ends connected to the derrick at the point 9^a and these ropes pass over pulleys 9^b fixed to the lower end 80 of the elevator frame. From the pulleys 9^b the ropes extend to screw eyes or the like 9^c fixed to the lower ends of the side bars 4^b of the elevator. The ends of the ropes 9 are tied or secured to the screw eyes 9^c. 85 Extending from the screw eyes 9^c are other ropes 10 which pass over pulleys 10^b fixed to the side bars 3^b of the elevator frame and have their ends connected to a pulley 10^a which they support. From Fig. 1 it 90 may be seen that drawing downwardly the pulley 10^a will cause the ropes 10 to move the elevator outwardly relatively to the elevator frame 3 and as the elevator moves outwardly the screw eyes 9^c will move away 95 from the pulleys 9^b and cause the derrick 5 to be swung on its pivots. The means for operating the pulley 10^a consists of a rope 11 having one of its ends fixed to a pulley 11^a carried by the cross-bar 1^d of the base. 100 The rope 11 passes from the pulley 11^a around the sheaf to the pulley 10^a then back through the pulley 11^a and is provided at its other end with a chain 11^b, the links of which are designed to be engaged by a hook 105 11^c formed on the single tree 11^a. By adjusting the single tree hook from the links of the chain 11^b the height to which the elevator will be raised may be adjusted. From this description it will be understood 110 that the ropes 6 and 11 may be simultaneously secured to the single tree for the purpose of actuating these ropes and the mechanisms to which they are connected, at one time. It is obvious that either one of the 115 ropes may be tensioned without the tensioning of the other rope when desired.

Attention is called to the fact that when the elevator frame 3 is swung from the position shown in Figure 1 to the position 120 shown in Figure 3, the cables 7 will raise the head 5^c of the derrick and this will cause the ropes 9 to draw the side bars 4^b of the elevator into the frame 3. In other words, the movement of the elevator frame 125 from substantially vertical to horizontal position, causes the ropes 9 to return the elevator 4 to its normal position.

I believe from the foregoing description that the construction and operation of my 130

apparatus will be apparent to those skilled in the art, and I am aware that various changes and modifications may be made in the construction illustrated without departing from the spirit of the invention or sacrificing any of its advantages.

What I claim and desire to secure by Letters-Patent is:

1. A hay stacker including a base provided with side bars, an elevator frame connected to said base, an elevator carried by said frame, means for simultaneously swinging said frame and extending said elevator relatively to said frame, and extension blocks 15 provided with clips designed to engage the side bars of the base.

2. A hay stacker including a base provided with side bars, an elevator frame connected to said base, an elevator carried by 20 the frame, means for simultaneously swinging said frame and extending said elevator relatively to said frame, and base extensions including blocks provided on their sides with clips adapted to engage the front 25 ends of said side bars, the blocks being also provided with clips designed to engage the top surfaces of said side bars.

3. A hay stacker including a base, an elevator frame connected to said base, an elevator 30 carried by said frame, means for simultaneously swinging said frame and extending said elevator relatively to said frame, a derrick, pulleys carried by the elevator frame, ropes connected to the derrick, passing 35 around said pulleys and connected to the lower end of the elevator, other pulleys connected to the upper portion of the elevator frame, ropes connected to the lower end of the elevator passing around the last mentioned pulleys and supporting a third pulley, a fourth pulley connected to the base 40 and a rope connected to the last mentioned pulley and passing around the third and fourth pulleys for drawing the second mentioned ropes to cause the elevator to be extended relatively to said frame.

4. A hay stacker including a base, an elevator frame connected to the base and provided with pairs of spaced bars, an elevator 50 carried by said frame and provided with side bars which are slidably mounted in the spaces between the pairs of spaced bars of

the elevator frame, plates secured to the side bars of the elevator and slidably engaging the bars of the elevator frame, and means 55 for simultaneously swinging said frame and extending said elevator relatively to said frame.

5. A hay stacker including a base, an elevator frame pivotally connected to the base 60 and movable into positions parallel to and at angles to the base, an elevator carried by the base, means for swinging said frame from its position parallel to the base and into its position at an angle to the base and simultaneously raising said elevator relatively to 65 said frame, and means for positively drawing said elevator downwardly relatively to the frame when said frame is moved from its position at an angle to the base into its position parallel to the base.

6. A hay stacker including a base member, an elevator frame member having its lower end pivotally connected to the base, an extensible elevator slidably engaging the 75 frame member, a derrick having its lower end pivotally connected to the base member, means connecting the derrick to the upper end of the frame member for causing the derrick to raise the frame member when the 80 derrick is swung in one direction, means for swinging the derrick in said direction, means for raising said elevator, guides mounted on one of said members, and flexible members 85 passing over said guides and having its ends connected to the upper portion of the derrick and to the lower end of the elevator for positively drawing the elevator downwardly when the derrick is swung in an opposite direction.

7. A stacker including a base, an elevator frame pivotally connected to the base, an elevator slidably mounted on the frame, means for swinging said frame relatively to the base and including a cable, means for raising said elevator simultaneously with the swinging of the frame and including a second cable, a draft member connected to the first mentioned cable, and adjustable means connecting the second cable and the draft 95 member to vary the height to which the elevator is raised.

ALBERT T. LOFTSGAARDEN.
